ROBOT LIP ACTION

Gilbert A. Magruder, Grand Rapids, Mich., assignor to Automatic Instrument Company, Grand Rapids, Mich., a corporation of Michigan

Application February 28, 1938, Serial No. 193,219

7 Claims. (Cl. 46—118)

This invention relates in general to a double lip action of a robot or manikin produced mechanically and electrically in connection with a radio reproducer or receiver for simulating the lip action of a person in making the same sounds.

Among the objects of the invention are to provide a robot with two lips and electro-mechanical means for operating them independently and in unison; to simulate the lip action of a person in speaking; to reproduce lip action from a radio receiver dependent upon tones of different frequency, power, or sound; to provide a lip action mechanism having a fast start and a slow stop; to provide a robot lip action in which the sounds corresponding to vowels cause a different action of the lips than for the sounds corresponding to consonants; to produce a simple, effective and efficient robot lip action operated from a radio receiver; and in general to produce the structure, device and lip action herein shown and described.

In the accompanying drawing illustrating a preferred embodiment of the invention—

Fig. 1 is a somewhat diagrammatic view illustrating an apparatus operated by a radio receiving set for producing a double lip action for simulating speech in a robot in accordance with this invention; and

Fig. 2 is an end view of the electro-magnetic device as shown in Fig. 1.

The present invention depends upon a change in frequency, volume, intensity, pitch or timbre for producing a distinguishable variation which may be communicated to the lips of a robot as coming from a radio loud speaker or receiving set. For example the upper lip may be connected to respond to vibrations of high frequency and the lower lip to vibrations of a low frequency. This makes it possible for distinguishing between the sounds of vowels and consonants. Ordinarily the oral passage is open to utter vowel sounds and is more or less restricted by the lips, tongue or teeth to produce the consonant sounds. Thus this lip action may be arranged so that the lip members will represent the mouth as being open for the production of vowels and more or less closed with either or both lips moving or open in producing the consonant sounds.

It is not represented that the speech as produced or reproduced by the radio or loud speaker must necessarily come from the mouth of the robot, but the speech reproduced for the robot might be adjacent thereto so that the lip action thereof would correspond to the speech as reproduced.

For the purpose of this invention it is unneces-

sary to go into the details of the radio equipment or loud speaker or the means for producing or varying the radio equipment which separates tones of high frequency from tones of low frequency. It is sufficient to represent that a radio receiver indicated generally by the reference numeral 4 has two outlet panels, one panel 5 for tones of high frequency, and 6 for tones of low frequency. These panels have terminals 7, 8 and 9, 10 respectively and are commonly provided with means forming no part of this invention for varying the frequencies available at said terminals.

Connected to the terminals 7 and 8 by conductors 11 and 12 respectively is a high frequency magnet 13 having a movable core or armature 14 connected to one end of a lever 15 mounted intermediate its ends upon a pivot 16 and connected to the other terminals 9 and 10 by means of conductors 17 and 18 is a low frequency magnet 19 having a movable core or armature 20 connected at one end of a lever 21 mounted intermediate its ends on a pivot 22.

In a manikin or robot represented by the broken outline 23 of a portion of a head are upper and lower lip members 24 and 25 mounted intermediate their ends upon pivots 26 and 27 respectively, the outer ends of the levers represented as the corresponding lips of the robot and the other or inner ends of the levers being connected by rods 28 and 29 respectively with the levers 15 and 21 respectively adjacent the ends thereof. The ends of the levers near the rods are connected to dashpot or retarding devices, each comprising a piston rod 30 connected to a piston 31 movable in a cylinder 32 and having a reduced vent opening 33 so that the action generally produced by the magnets is for rapid starting and slow stopping, or as applied to the lips is fast opening and slow closing.

In the operation of this lip action it will therefore be apparent that depending upon the power supplied to the magnets 13 and 19 each lip member may be operated more or less, separately, or in conjunction to produce a corresponding variation of the lip members, thereby simulating the lip action of a person in actually saying the same thing.

It is intended that a robot equipped with this lip motion will be operated by an electrical reproducer either in connection with a receiver for radio or a sound reproducer as shown more or less diagrammatically in Fig. 1. A disc sound record 35 is placed upon a turntable 36 rotated by a motor 37, the sound being picked up in a well known manner by a stylus 38 carried by a tone

arm 39 mounted to turn and tilt upon a shaft 40. Electrical conductors 41 and 42 connect the tone arm to terminals 43 and 44 respectively of the radio receiver where the vibrations produced by the record are amplified, the tones of high and low frequencies are separated or filtered and the resultant electrical impulses are given to the magnets 13 and 19 to impart motion to the lips 24 and 25 as above set forth.

It is obvious that various changes in the forms of the lip members, the extent of their movements, the intensity of the current or the frequency applied to the operating magnets may be varied by suitable means without departing from the spirit and scope of the invention.

I claim:

1. In a robot lip action, a pair of lip members, and means connected independently thereto for separately operating the lip members to move alone and together and thus simulate the lip action of a person.

2. In a robot lip action, upper and lower lip members, means connected independently thereto for operating the lip members separately, and electro-responsive means depending upon the different intensity of the sound produced for operating the lip members separately and together in accordance therewith.

3. In a robot lip action, the combination with a radio receiving set having outlets for currents of different frequencies, of electro-responsive means separately actuated by said different frequencies, and a pair of lip members independently connected to and separately actuated by said electro-responsive devices for moving the lips separately and together and thus simulating the lip action corresponding to tones of high and low frequency.

4. In a robot lip action, a pair of movable lip

members, a pair of magnets actuated by currents of different intensities, each having a core member moved thereby and an independent connection between each of the core members and a corresponding movable lip member for moving it to simulate lip motion for consonants or vowels in accordance with the intensity of the current.

5. In a robot lip action, a pair of lip members pivotally mounted intermediate their ends, a pair of magnets actuated by currents of different frequencies and having movable cores, means for transmitting the movement of the cores independently and individually to the corresponding lip members to simulate consonant and vowel lip movements, and retarding means for the said moving means to cause a slow stopping movement of the lips.

6. In a robot lip action, upper and lower independently movable lip members, a separate magnet for each member actuated by currents of different intensities, means including a pivoted lever and a rod for connecting each magnet to the corresponding lip member and a retarding device in connection with each lever for slowing the speed of movement imparted by the magnet to the lip member.

7. The combination with a robot lip action for upper and lower lips; of a sound record, means for reproducing the sound, and electrical means for separating sounds of different frequencies; the lip action comprising magnets actuated by different frequencies; and separate connections from the magnets to the upper and lower lips for moving them independently in accordance with the reproduction of the sound record to simulate the movement of lips in making the sounds.

GILBERT A. MAGRUDER.
